(57) **CLAIM**

The ornamental design for a baby changing pad, as shown and described.

DESCRIPTION

FIG. 1 is a top, front, left side perspective view of a new design for a baby changing pad;

FIG. 2 is a top view thereof;

FIG. 3 is a bottom view thereof;

FIG. 4 is a right side view thereof, the left side view is a mirror image thereof;

FIG. 5 is rear view thereof; and,

FIG. 6 is a front view thereof.

The broken lines shown in the drawings depict portions of the baby changing pad that form no part of the claimed design.
